UNITED STATES PATENT OFFICE.

DAVID R. HAWLEY, OF SEBRING, OHIO, ASSIGNOR OF ONE-HALF TO JAMES SIMPSON,
OF SEBRING, OHIO.

SLIDING-JAW WRENCH.

1,122,921.

Specification of Letters Patent. Patented Dec. 29, 1914.

Application filed July 15, 1914. Serial No. 851,181.

To all whom it may concern:

Be it known that I, DAVID R. HAWLEY, a citizen of the United States of America, residing at Sebring, in the county of Mahoning and State of Ohio, have invented certain new and useful Improvements in Sliding-Jaw Wrenches, of which the following is a specification, reference being had therein to the accompanying drawing.

This invention relates to sliding jaw wrenches, and has for its object to provide a device of such class, in a manner as herein-after set forth, whereby the sliding jaw of the wrench can be quickly adjusted to the desired position with respect to the fixed jaw.

Further objects of the invention are to provide a sliding jaw wrench, which is simple in its construction and arrangement, strong, durable, efficient and convenient in its use, readily set up and comparatively inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claim hereunto appended.

In the drawings wherein like reference characters denote corresponding parts throughout the several views:—

Figure 1 is a side elevation of a wrench in accordance with this invention, Fig. 2 is a longitudinal sectional view, and Fig. 3 is a cross section on line X—X of Fig. 2.

Referring to the drawings in detail, 4 denotes a shank having its forward and its rear edge smooth and the said shank 4 is rectangular in cross section.

The shank 4 intermediate its ends is formed with a longitudinally extending opening 5, and said shank has one edge of the end portion beveled as at 6, the said beveled portion 6 being on the rear edge of the shank, the forward edge of the shank extending in the same plane from end to end. The beveled end portion of the shank terminates in a cylindrical peripherally threaded extension 7. The shank 4 is furthermore provided with a longitudinally extending pocket 8, which communicates with the

inner end of the opening 5, and the shank 4 is furthermore provided with a transverse opening 9, which registers with the pocket 8. The reference character 10 denotes a handle formed with a longitudinally extending opening. The wall 12 of the opening 11 extends in the same plane throughout, while a portion of that wall of the opening 11, which opposes the wall 12 and which is indicated by the reference character 13 is beveled. The beveled edge 6 of the shank 4 is adapted to be positioned against the beveled portion 13 of that wall of the opening 11, which is opposite the wall 12. Mounted upon the threaded extension 7 and abutting against the handle 10 is a retaining nut 14. The reference character 15 denotes a sliding jaw having an integral strap 16, which surrounds the shank 4, whereby the jaw 15 is slidably connected to said shank 4.

Projecting inwardly from the jaw 15 and extending into the opening 11 at a point between the shank 4 and the wall 12 is a stem 17 having its inner edge provided with teeth 18.

Extending transversely of the opening 5 is a shaft 19 upon which is rotatably mounted a toothed wheel 20, which permanently engages with the teeth 18, so that when the wheel 20 is rotated, the stem 17 will be shifted to adjust the position of the sliding jaw 15. The sliding jaw 15 is retained in its adjusted position through the medium of a toothed locking member 21, which is mounted in the pocket 8 and bears against a coiled spring 22, which is also seated in the pocket 8, and said spring 22 normally maintains said member 21 in engagement with the teeth of the wheel 20 to prevent rotation of the latter. The member 21 is actuated through the medium of a pin 23, which projects through the opening 9 and also through an opening 24, formed in the handle 10, the opening 24 alining with the opening 9.

When it is desired to release the toothed wheel 20, the member 21 is shifted toward the bottom of the pocket 8 by pressure upon the pin 23.

What I claim is:—

A sliding jaw wrench comprising a shank formed with a longitudinal extending opening and having a longitudinal pocket connected at one end with said opening, a handle mounted upon one end of the shank,

a jaw slidable upon said shank and having a stem extending into the handle to oppose the forward edge of said shank and having its inner edge toothed, a toothed wheel rotatably mounted in said opening and permanently engaging the teeth of a shank and being capable when rotated to shift said slidable jaw, a spring controlled locking member carried by the shank and engaging said wheel to arrest rotation thereof, said locking member including a pin projecting from

the shank and handle, and said shank and handle being provided with openings to permit of the shifting of the pin for actuating said locking member.

In testimony whereof I affix my signature in the presence of two witnesses.

DAVID R. HAWLEY.
